UNITED STATES PATENT OFFICE

HUGO H. WERMINE, OF VILLA PARK, ILLINOIS, ASSIGNOR TO BELDEN MANUFACTURING COMPANY, OF CHICAGO, ILLINOIS, A CORPORATION OF ILLINOIS

ELECTRIC CONNECTER PLUG

Application filed June 11, 1927. Serial No. 198,022.

This invention relates to electric connector plugs, and more particularly to the female part of a separable connector plug.

The principal object of the invention is to provide a plug of the type referred to, which will be practically unbreakable. Other objects of the invention are to provide a plug of the type mentioned which consists of relatively few parts of simple and easily constructed form; to provide such a plug of few parts which can be quickly and easily assembled and which will not readily become disassembled; and, in general, to provide an improved plug of the class described.

Other objects and advantages of the invention will be understood by reference to the following specification and accompanying drawings, in which I have illustrated a plug embodying a selected form of the invention and in which drawings:

Fig. 1 is a side elevation.

Fig. 2 is a section on an enlarged scale on the line 2—2 of Fig. 1.

Figs. 3 and 4 are sections on the lines 3—3 and 4—4, respectively, on Fig. 2, and

Fig. 5 is a perspective of one of the parts constituting the plug.

In the drawings, I have indicated a plug comprising a main body portion 6, an auxiliary body portion 7, terminal members 8 and 9, and contact members 10 and 11 connected respectively to the said terminals 8 and 9. The main body portion 6 is preferably cylindrical in form and is provided with a knurled or fluted end portion 12 of enlarged diameter for facilitating gripping and manipulation of the plug. The main body portion is provided with a pair of recesses or apertures 14 and 15 extending longitudinally thereof, and in which recesses the terminals 8 and 9 are respectively disposed. The main body portion is also provided with an outwardly projecting annular rib 16 which is adapted to interlock with a similar rib on a male connector plug 13, such as indicated in dotted lines in Figure 2.

The contact member 11, preferably in the form of a screw-threaded metallic shell, is provided with an inwardly extending flange

17 and is seated about the inner end of the main body portion with the flange portion 17 engaging the end of the body and thereby serving to position the contact shell thereon. The inwardly extending flange 17 is provided with a section 18 of increased width, and this section is slotted as indicated at 19 to permit the passage of the terminal 9 therethrough. The inner portion 20 of the widened section of the flange is inwardly offset approximately the thickness of the terminal member, and the terminal member is bent over to provide a leg portion 21 which engages the said inwardly offset portion 20 and is thus positioned in the aperture 15.

The contact shell 11 and terminal 9 are held in position on the plug body 6, preferably by means of the auxiliary body portion 7. This auxiliary body portion comprises an inwardly extending stem 22 which is seated in a conforming recess 23 in the main body portion, and a flange portion 24 which overlies the end of the main body portion and is effective to clamp the inwardly extending flange 18 of the contact shell against the said inner end of the main body member.

In the present embodiment of my invention, I prefer to mount the terminal member 8 and contact member 10 to which it is connected, on the auxiliary body portion 7, and accordingly I make the contact member 10 in the form of a rivet having an enlarged head portion 25 seated in a recess 26 provided in the inner end of the inwardly extending stem 22. It will be understood that the auxiliary body portion 7, terminal member 8, and contact member 10 are thus permanently united, and it will be observed that the contact member 10 is disposed substantially axially of the contact shell 11, whereby the plug is adapted to fit the standard type of Edison lamp socket.

I prefer to interlock the main body portion 6 and the auxiliary portion 7 so that they will not be readily separable, and for this purpose I provide a dove-tail form of interlocking connection. As is clearly shown in Figs. 2, 3 and 5, the inwardly extending stem portion 22 of the auxiliary body member is of dove-tail—i. e., flaring—

shape, and, as above noted, the recess 23 in the body portion 6 conforms to the shape of the stem.

The body portions 6 and 7 are preferably made of relatively soft and resilient rubber or like material so that these parts are practically unbreakable even when subjected to the hardest use and most careless handling, and the fact that these parts are resilient permits one or both of them to be distorted sufficiently to permit assembling of the above-described dove-tail interlocking connection. It will, of course, be understood that either one of the parts may be made of such resilient material as will permit sufficient distortion thereof to permit assembling with the other part, which may be made of hard or firm material.

This form of interlocking connection has the additional advantage, due partly to the expansive tendency of the resilient material, of normally tending to urge the auxiliary body member to move towards the main body member so as to effectively clamp the contact shell and its terminal member in operative position on the main body member. The inwardly extending stem portion 22 of the member 7 is preferably provided with a pair of notches 27 and 28 which are adapted to be aligned with the apertures 14 and 15 in the body portion 6 to permit passage terminals and to facilitate assembling of the two body parts. It will be noted that the contact shell 11 is prevented from rotating about the body member 6 because of its interlocking engagement with the terminal 9 and the fact that the terminal 9 is disposed in the relatively close fitting aperture 15, which, of course, prevents lateral movement of the terminal.

The above described details of construction being illustrative of a selected embodiment of my invention, it will be understood that the scope of the same should be determined by reference to the following claims, which should be construed as broadly as possible consistent with the state of the art.

I claim as my invention:

1. An electric plug connector, comprising a main body member having a recess therein, an auxiliary body member interlocked therewith, one of said members being formed of resilient material so as to be capable of being distorted for permitting interlocking thereof with the other member, and a terminal disposed in the recess in said main body member and provided with a portion engaging said auxiliary member, whereby the terminal is retained in said aperture.

2. An electric plug connector, comprising a main body member having a recess therein, an auxiliary body member interlocked therewith, one of said members being formed of resilient material so as to be capable of

being distorted for permitting interlocking of said members, a terminal disposed in said recess, and a contact member connected to said terminal, said terminal and contact member being provided with means engaging said auxiliary member and thereby maintained in operative position relative to said main body member.

3. An electric plug connector, comprising a main body member having a recess therein, a contact shell disposed around said body member and having an inwardly projecting flange fitting over the inner end of said main body member, said shell being thereby held against outward movement along said body member, a terminal disposed in the recess in said main body member and having its inner end portion bent over and interlocked with said flange on said shell and thereby locked against outward movement in said recess, and an auxiliary body member interlocked with said main body member so as to be normally inseparable therefrom and effective to maintain said contact shell and terminal interlocked.

4. In an electric plug connector, the combination of a relatively soft rubber body member having a pair of apertures extending longitudinally therethrough, a terminal and a contact shell electrically connected and disposed respectively in one of said apertures and around said body member, a relatively soft rubber auxiliary body member, another terminal and contact member connected together and secured to said auxiliary member, and dove-tail means for interlocking said auxiliary member and main body member with the terminal carried by the auxiliary member disposed in the other of said apertures.

5. In an electric plug connector, the combination of a relatively soft rubber body member having a pair of apertures extending longitudinally therethrough, a terminal and a contact shell electrically connected and disposed respectively in one of said apertures and around said body member, said shell having an inwardly extending annular flange at its inner end seated against the inner end of said body member, a relatively soft rubber auxiliary body member, another terminal and contact member connected together and secured to said auxiliary member, and dove-tail means for interlocking said auxiliary member and body member with the terminal carried by the auxiliary member disposed in the other of said apertures, said auxiliary member being provided with means engaging said inwardly extending flange to retain said contact shell on said body member.

6. In a female electric plug connector, the combination of a pair of body parts, one of which is provided with a pair of apertures extending therethrough, said parts

having dove-tailed interlocking engagement, and one of said parts being formed of resilient material and capable of being distorted to permit such interlocking engagement to be effected, a terminal and a contact shell electrically connected and disposed respectively in one of said apertures and around the apertured body part and provided with means engaging the other body part whereby the terminal and shell are retained in said position, and another terminal and contact member electrically connected and carried by the said other body part, this said terminal being disposed in the other of said pair of apertures and the contact member substantially coaxially of said contact shell.

7. An electric plug connector comprising a main body member having an aperture therein, an auxiliary body member, means provided on each of said body members integral therewith for interlocking said body parts, a terminal disposed in said aperture and secured to said auxiliary body member, and a contact member carried by said auxiliary body member and serving to secure said terminal thereto.

8. In a female electric plug connector, the combination of a pair of body members of relatively soft rubber interlocked together to serve as a unitary substantially unbreakable plug body, one of said body members being provided with an aperture therein, and a terminal member disposed in said aperture and engaging a portion of the other body member whereby the terminal is maintained in said aperture.

9. In a female electric plug connector, the combination of a main body member provided with an aperture extending longitudinally therethrough, a terminal member disposed in said aperture, a contact shell disposed about said body member and provided with an inwardly extending annular flange engaging one end of said body member for positioning the shell on the member and also contacting with a portion of said terminal for establishing electrical connection therewith, and an auxiliary body member provided with a portion overlying said flange and having interlocking engagement with said body member, one of said body members being made of resilient material capable of being distorted to permit assembling of the body parts in said interlocking engagement, the form of the interlocking connection being such that it normally tends to urge said auxiliary body member to move towards said main body member, whereby said auxiliary member is effective to clamp said shell and terminal in operative position on said main body member.

10. A female connector plug of the class described, comprising a main body part having a pair of openings therein, a pair of

terminal members respectively positioned in said openings, a contact element carried by said main body part and electrically connected to one of said terminals, an auxiliary body part having interlocking engagement with said main body part, a contact element carried by said auxiliary body part and electrically connected to the other of said terminals, said main and auxiliary body parts being relatively distortable to permit assembly thereof into said interlocking engagement.

DISCLAIMER

1,820,333.—*Hugo H. Wermuth*, Villa Park, Ill. ELECTRIC CONNECTOR PLUG. Patent dated August 25, 1931. Disclaimer filed October 9, 1931, by the assignee, *Belden Manufacturing Company*.

Hereby enters this disclaimer to the subject matter of:

Claim 1 of said Letters Patent, except insofar as said claim relates to an electric connector plug having a terminal concealed or enclosed within a recess in the main body portion for receiving in contact therewith, within said recess, a prong of another connector;

Claim 2 of said Letters Patent, except insofar as said claim relates to an electric connector plug having a contact member exposed on the exterior of the structure, and in which the terminal and contact member are separate and distinct elements, each of which is provided with means engaging the auxiliary body member.
